RICHARD T. NEWTON, OF NEW YORK, N. Y., ASSIGNOR TO ARMS PRODUCTS COMPANY,
OF NEW YORK, N. Y., A CORPORATION OF NEW YORK.

EXPLOSIVE MISSILE.

1,369,701.

Specification of Letters Patent. Patented Feb. 22, 1921.

Application filed February 12, 1918. Serial No. 216,689.

To all whom it may concern:

Be it known that I, RICHARD T. NEWTON, a citizen of the United States of America, residing in the city, county, and State of New York, have invented certain new and useful Improvements in Explosive Missiles, of which the following is a specification.

My invention relates to explosive missiles and generally to explosive missiles whether they be of the hand-thrown or charge projected type. Although I have shown the invention in the accompanying drawings as a projectile of the type commonly known as grenades, which may be thrown by hand or fired from a gun and are generally of relatively small size, the features to which my invention relates are applicable to projectiles of any type and are perhaps applicable more particularly to projectiles of the larger gun sizes, such as are commonly known as shells. The particular feature to which my invention relates is a guard which renders the projectile relatively safe during handling, but releases the firing mechanism after the projectile is in flight. The firing mechanism may be either of the percussion type or of the time fuse type, or both may be combined in a single projectile, and my invention is applicable to all three types. Preferably, the guard is so constructed that on its release of the firing mechanism, the guard moves to a position in which it acts as a vane for directing the flight of the projectile. The vanes are preferably so constructed that they impart to the projectile, during its flight, an axial rotation similar to that ordinarily imparted to a projectile by the rifling of the barrel through which it is discharged. A further feature of the invention is to provide a combined guard and guide vane in which the features specified are embodied, which, at the same time, is of simple and cheap construction, readily applied to the projectile, and at all times efficient for its several purposes.

In the accompanying drawings,

Figure 1 is a side-elevation of a projectile of the percussion grenade type, to which my invention is applied in one form;

Fig. 2 is a plan thereof;

Fig. 3 is a longitudinal section therethrough;

Fig. 4 is a partial side elevation of the guard vanes provided with lateral flanges inclined to the axis of the projectile and designed to impart to the latter, axial rotation during flight; 55

Fig. 5 is a longitudinal section through a projectile of the grenade type, not only showing a guard of further modified construction, but a modified grenade construction in which the explosive charge may be fired either by a percussion member or a time fuse; 60

Fig. 6 is a section on the line 6—6, Fig. 5; 65

Fig. 7 is a side elevation of the vane arm, indicating the position assumed thereby when the vane is locked in trailing position;

Fig. 8 is a vertical section through a portion of a guard of modified vane construction; 70

Fig. 9 is a section on the line 9—9, Fig. 8;

Fig. 10 is a horizontal section through the vanes showing their relative location when in trailing position; and 75

Fig. 11 is a side elevation of a vane provided with spiral ribs for imparting axial rotation to the projectile.

Ordinarily, a projectile of the type to which the present invention relates must be handled very carefully prior to, and even at the moment of firing, in order to prevent explosion of the charge therein through accidental displacement of the firing mechanism. In some of the hand grenades now in use, it is necessary, after removal of the safety pin, to hold the guard lever positively against the side of the grenade. If accidentally released, the spring-pressed striker fires the fuse and the grenade explodes prematurely. In other grenades, the striker is held against accidental displacement by pins which are withdrawn by the rotation of a wind vane during the flight of the grenade. Unless the vanes act, the grenade strikes harmlessly and may be returned by the enemy. By the present construction I have provided not only an efficient and relatively safe guard against premature explosion of the missile, but I have also utilized this guard to form a guide which holds the missile head-on during its flight and preferably imparts thereto an axial rotation substantially equivalent to that nor- 95

mally imparted to a projectile by the rifling of the gun barrel through which it is fired.

In Figs. 1 to 3 I have shown the projectile in the form of a grenade comprising a casing or shell 20, more or less egg-shaped, and having screwed into one end thereof a head piece 21, carrying the firing pin 22. At the bottom of the well 23 in which the firing pin works, is seated the percussion cap 24 which ignites the detonator 25, thus firing the charge 26 which fills the body of the casing. The firing pin 22 is normally held against movement by the fragile cross pin 27, which is readily broken upon impact against the firing pin head 28.

Obviously, the firing pin must be guarded against accidental impact during the handling of the grenade prior to its discharge. For this purpose, I have pivoted to the casing 20 at 29 and 30 a pair of arms 31, 32, the free ends of which comprise webs 33-34, approaching each other and overlapping to receive a locking cross pin 35 of any suitable type. I have here shown it as a cotter pin, the eye end of which is enlarged to permit its ready withdrawal. The wings 33-34 are notched out at 36-37 to receive the margins of the firing pin head 28, thus holding the latter against accidental displacement into engagement with the detonating cap 24. Flanges 38-39 are preferably formed on the webs 33-34 and extend at right angles to the plane of the latter in order to not only further protect the cap 28 against accidental blows, but also to assist in swinging the arms 31-32 from their guard position to their trailing position, in which they act as guide vanes during the flight of the missile. This movement of the flanges 38 is caused by the pressure exerted upon the flanges by the air as the missile speeds therethrough. The air column entering between the flanges 38, impinges upon the cap 37 and tends to force the flanges 38-39 apart, thus throwing the arms 31-32 around on their loose pivots 29-30 to their trailing position. It is obvious that the firing pin is now exposed, so that on impact against its head 37, the fragile retaining pin 27 is broken and the firing pin driven in against the detonating cap 24.

In Fig. 4 I have indicated a construction of the flanges 38-39 in which they are angled to the direction of travel, so that they impart to the missile an axial rotation during its flight. This tends to insure precision of direction in a manner well understood in the art.

If desired, means may be provided for holding the arms 31-32 in trailing position. Thus, I have indicated in dotted lines, Fig. 1, a snap catch arrangement operating by centrifugal force. This device comprises a hook member 40 pivoted at 41 to the arm 31 and of such length that when both arms are

swung back to trailing position, the hook 40 will swing into engagement with the eye 42 carried by the arm 32. Both arms are preferably made of channel section, folded to shape from sheet metal, so that the hook 40 may readily be accommodated in the interspace between the wings 33 of the arm 31.

In order to steady the arms and relieve the pins 29-30 from strain, channels 43-44 are formed in the shell 20 to receive the arms 31-32, and these channels are continued on the opposite sides of the pivots 29-30 by the channels 45-46, which form steadyng guideways for the arms in their trailing position.

In Fig. 5 I have shown the projectile with a head 47 screwed into one end and carrying not only a percussion pin 48 to co-operate with the firing cap 49, but also a fuse 50 adapted to be ignited by the cap 51 on impact thereagainst by the firing needle 52, under the action of its spring 53. The fuse 50 or cap 49 (or both) serves to ignite the detonator 54 which fires the entire charge within the projectile casing. In order to safeguard the grenade against premature explosion, I utilize, in this modification, but a single guard arm 55, the web 56 of which is notched at 57 to engage the firing pin head 58, and also notched at 59 to engage the lug 60 extending from the head of the needle 52 and overlying the inclined upper edge of the fingers 61, through which passes the locking pin 62. On the removal of the locking cotter pin 62, the arm 55 is free to swing around to such position that the web 56 takes a trailing position in a manner similar to that indicated in Fig. 3. In the present case, the web 56 is sufficiently extended to perform the functions of both webs of the two levers indicated in the preceding construction. In the present case also, the arm 55 is bell-crunked and is centrally pivoted on a pin 63 on the casing. As the web 56 moves to the left during the flight of the projectile, it frees not only the head 58 of the firing pin 48, but also the lug 60 of the needle pin 52. The latter is immediately driven by its spring 53 against the cap 51, thus exploding the latter and igniting the fuse 50, which may, of course, be timed as desired. Should the missile reach its objective before the fuse is consumed, it is fired by the percussion pin 48. If the percussion pin is not operated on impact, or if the fuse burns out before the missile strikes, then the detonator charge 54 is ignited by the fuse and the grenade thus exploded.

In order to lock the wing piece 56 in its trailing position, its pivot pin 63 is given a T form, and the pivoting eye for the arm 55 is extended on one side in the form of a slot 64, so that when the arm swings around to the position indicated in Fig. 7, the shank 130

of the T-pin 63 automatically enters the slot 64 and thus holds the arm 55 rigidly in position.

In Figs. 8 and 9 I have shown a modified construction of the webs of the guard arms. These webs 65—66 are now curved into semi-cylindrical form and provided with lugs 67 to receive the cotter pin 68. Flanges 69, notched at 70, engage the head of the firing pin 71 and hold the latter against accidental displacement in precisely the same manner as heretofore. When the arms are swung around to trailing position, the webs form oppositely faced, trough-shaped vanes 15 which are equally effective in guiding the missile on its flight.

In Fig. 11 I have shown the web as a cylindrical element 72 carried by a single arm 73 and provided with circumferential 20 spiral fins 74, (of which only two are indicated on the drawing) which impart a twirling motion to the projectile as it flies. In this construction, I have shown the arms 73 as provided with a flange 74^a engaging the 25 head 75 of the firing pin. This head is perforated at 76 to receive the cotter pin 77 which is drawn out of its locking position when the projectile is about to be fired. The flange 78 on the wing piece 74 is pierced 30 to receive the locking pin.

I have shown the arms 31—32 provided with fins or vanes, which not only form a guard for the firing means, but also move to guiding position on their release of the 35 firing means. It is clear, however, that either function may be utilized by itself. Thus, if merely a guard and not a guide is desired, the arms may be pivoted to the casing of the grenade in an open bearing such 40 that on swinging backward from guard position, the arms would drop off. Contrariwise, if a guide and not a guard is wanted, the vanes may be fixedly attached to the grenade in guiding position.

The grenade may be thrown by hand, or 45 it may be fired from a gun. In order to adapt it to the usual practice in the latter respect, the rear end of the grenade is provided with a threaded boss 79 on which the 50 cartridge holder 80 is screwed. The latter has a series of holes 81 in its wall, through which the casing of the shell 82 is blown when the latter is fired, so that both the holder and cartridge are carried by the 55 grenade during its flight. On the other hand, the construction of the missile is such that it may be inserted bodily in the breech of a gun, preferably of smooth bore, and be projected by a special cartridge or shell.

In larger sizes, this would be especially 60 desirable. It will be noted, in this connection, that the arms 31—32 lie within the greatest overall transverse diameter of the projectile, and furthermore, that at the point of greatest 65 diameter, a packing ring 83 is formed by

interrupting the longitudinal seams which, with the circumferential seams, divide the casing of the shell into shrapnel segments.

Various other modifications and developments of the device will readily occur to those skilled in the art which do not depart from what I claim as my invention.

I claim:

1. An explosive projectile having at its head end firing means, and guard means 75 therefor normally protecting said firing means but moving from protecting to trailing position at the rear of the projectile during the flight of the projectile.

2. An explosive projectile having at its 80 head end firing mechanism and guide means normally engaging said firing mechanism to hold it against actuation during the initiation of the missile's flight, but moving into operative guiding position at the rear of the 85 projectile after said flight has been initiated.

3. An explosive projectile having firing 90 mechanism at its head end, and guide means normally engaging said mechanism to hold it against actuation, but moving rearward thereof into guide position after the flight of the projectile is initiated.

4. An explosive projectile having at its head end a percussion member and guide means normally holding said member 95 against actuation but automatically releasing the same and moving to guide position at the rear of the projectile during the flight of the missile.

5. A missile having at its head end means 100 for exploding the same, in combination with guide means normally guarding said explosive means against operation, but automatically releasing said explosive means and moving to guiding position at the rear of 105 the projectile during the flight of the missile.

6. A missile having a detonating charge, a percussion member at the head of the missile for firing the detonator, and guide means normally holding said percussion 110 member against actuation, but automatically releasing the same and moving to guiding position at the rear of the projectile during the flight of the missile.

7. An explosive missile having impact firing means at its head end, means engaging said firing means to normally prevent the operation thereof but operatively displaced during the flight of the projectile from guard position under the influence of wind pressure thereon, together with detachable means carried by the projectile for holding said guard means normally in operative position.

8. An explosive missile, impact firing 125 means projecting therefrom, guard means engaging said firing means but operatively displaced from guard position during the flight of the projectile under the influence of wind pressure thereon, and removable 130

means for normally holding said guard means in operative position.

9. An explosive missile having impact firing means, guard means engaging said firing means to prevent accidental or premature operation thereof, and removable means normally carried by the projectile to hold the guard means in operative position, but

on removal freeing said guard means to permit the latter to be operatively displaced out of guard position under the influence of wind pressure thereon during the flight of the projectile.

In testimony whereof I have signed my name to this specification.

RICHARD T. NEWTON.
